[57] CLAIM

The ornamental design for a portable golf ball washer, as shown.

DESCRIPTION

FIG. 1 is a perspective view of a portable golf ball
washer showing my new design;

FIG. 2 is a top plan view thereof;

FIG. 3 is a bottom plan view thereof;

FIG. 4 is an end elevational view taken from the right of
FIG. 1;

FIG. 5 is an end elevational view taken from the left of
FIG. 1;

FIG. 6 is a rear elevational view thereof; and

FIG. 7 is a front elevational view thereof.

FIG. 1.FIG. 2.FIG. 6.FIG. 7.FIG. 8.FIG. 10.FIG. 12.
